US0D1047574S

(12) **United States Design Patent** (10) Patent No.: **US D1,047,574 S**
(45) Date of Patent: ** Oct. 22, 2024

(54) **POT LID**

(71) Applicant: **Tineco Intelligent Technology Co., Ltd.**, Suzhou (CN)

(72) Inventor: **Haoqiang Zhang**, Suzhou (CN)

(73) Assignee: **TINECO INTELLIGENT TECHNOLOGY CO., LTD.**, Suzhou (CN)

(**) Term: **15 Years**

(21) Appl. No.: **29/832,445**

(22) Filed: **Mar. 28, 2022**

(30) **Foreign Application Priority Data**

Sep. 30, 2021 (CN) 202130652121.5

(57) **CLAIM**

The ornamental design for a pot lid, as shown and described.

DESCRIPTION

FIG. 1 is a perspective view of a pot lid, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines shown in the views depict portions of the pot lid that form no part of the claimed design.

1 Claim, 4 Drawing Sheets
